UNITED STATES PATENT OFFICE.

ARTHUR C. DAMAN, OF DENVER, COLORADO.

DRIER.

Application filed June 26, 1922. Serial No. 570,822.

To all whom it may concern:

Be it known that I, ARTHUR C. DAMAN, citizen of the United States of America, residing at Denver, in the county of Denver 5 and State of Colorado, have invented certain new and useful Improvements in Driers, of which the following is a specification.

This invention relates to driers of the revolving drum type and has for its principal object the provision of a device of this character in which materials of a sticky, viscous nature will be prevented from adhering to the inside of the drum.

Another object of the invention is to provide a furnace for a device of this character which is so constructed as to reduce the burning out of the fire box lining to a minimum.

A further object of the invention resides 20 in the novel construction of the furnace which reduces the heat losses due to wall radiation to a minimum and results in high efficiency in the heating of the air for the drier.

Other objects and advantages reside in 25 the detail construction of the improved drier, which result in simplicity, economy and efficiency, and which will become more apparent from the following description.

In the following detailed description of 30 the invention reference is had to the accompanying drawings which form a part hereof. Like numerals refer to like parts in all views of the drawings and throughout the description.

In the drawing:

Fig. 1 is a side elevation of the improved drier, partly broken away to show the interior construction thereof.

Fig. 2 is a vertical section taken on the line 2—2, Fig. 1.

Fig. 3 is a similar section taken through the furnace on the line 3—3, Fig. 1.

Fig. 4 is a horizontal section through the 45 furnace taken on the line 4—4, Fig. 3.

Fig. 5 is a similar section taken on the line 5—5, Fig. 3.

Let the numeral 10 designate a cylinder or drum which serves as the drier proper. 50 Drum 10 is slightly inclined toward its rearward or discharge end and is of the proper diameter and length to suit the capacity required. Drum 20 is surrounded by two bearing rings 11 and 12 which ride on supporting rolls 13 and 14 respectively. A

ring gear 15 also surrounds the drum 10 and meshes with a drive pinion 16 carried on a counter shaft 17 which in turn is driven by means of a belt pulley 18, or in any desired manner.

The higher extremity of drum 10 is open to the interior of a furnace 19, the lower extremity opening into a housing 20. An exhaust fan 21 is supported on the housing 20 and discharges into a stack 22.

Mounted above the furnace 19 and opening into the drum 10 is a feeder 23 provided with a feed hopper 24. A shaft 25 carrying a helical scraper 26 extends throughout the entire drum 10 into the feeder 23. Shaft 25 is driven by means of a chain 27 from the countershaft 17. Shaft 25 and feeder 23 are slidably mounted by means of horizontally adjustable bearings 28. The bearings 28 are so adjusted as to bring the periphery of the scraper 26 close against the inner wall of the drum 10, as shown in Fig. 2. Scraper 26 rotates in the opposite direction to the drum 10.

The furnace 19 consists of an outer, surrounding wall 29 supporting an arch 30 which completely closes the top of the furnace. The drum 10 opens to the furnace 19 at the high point below arch 30. Contained within the furnace is a fire box, 31, consisting of two side walls 32 and back wall 33. Back wall 33 extends entirely across the furnace 19. Walls 32 and 33 are spaced away from the outer walls 29 thereby forming air passage-ways 34 at each side of the fire box 31 and a combustion and settling chamber 35 at the rear thereof. Walls 32 and 33 are stopped below the arch 30.

Fire box 31 is provided with the usual grates 36 and an ash pan bottom 37.

Openings 41 are left in the lower portion of the walls 32 and allow communication between the space below the ash pan bottom 37 and the passage-ways 34.

Suitable doors and dampers are arranged in the outer walls 29 communicating with the space below the ash pan bottom, the ash pan and the fire box, respectively numbered 38, 39, and 40.

The operation of the furnace is as follows: The fire is carried on the grates 36, air for the proper combustion thereof being admitted through the door and damper 39. Additional air is admitted through the door and damper 38 into the space below the ash

pan passing from thence out the openings 41 and up the passageways 34 over the entire length of the walls 32, into the combustion space under the arch 30 thence into 5 the drum 10, with the combustion gases of the fire, and, through the fan 21, up the stack 22.

The advantages of this system of admitting the air are many and it is one of the 10 principal features of the invention. It allows a large volume of heated air to be drawn through the drum 10 without it being necessary to pass all of the air through the fire bed and cause too rapid combustion. The 15 air is preheated by its passage around the fire box and is admitted to, and absorbs heat from the combustion proper at the hottest point before entering the drum 10. The rising column of air at each side of the fire 20 box absorbs all heat radiated from the walls thereof which in the usual construction is wasted. The temperature of the outer walls is kept low by the rapidly moving air between them and the fire box. The arch, 25 which in the usual type of construction burns out rapidly and must be often replaced, is protected by the moving layer of heat-absorbing air which travels up the inner side of the outer walls and along under 30 the arch. The heat from the fire is rapidly carried into the drum 10 and no part of the furnace is subjected to an accumulation of excessive temperature.

The course of the material being dried 35 through the drier is as follows: From the feed hopper 24, the material is carried into the drum 10 by means of the helical scraper 26, which, in the feeder 23, acts as a spiral conveyer. It is carried through the 40 revolving drum 10 by gravity, each particle as it falls from the ascending side of the drum advancing itself slightly because of the slant of the drum. Any particles which adhere to the drum are scraped loose by the 45 revolving scraper 26, the edges of which are constantly moving along the inner surface of the drum at an angle which tends to work all material toward the discharge end of the drum 10. The material falls from the open 50 discharge end of the drum into the housing

20 and is removed through a clean out door 42.

While I have described and illustrated herein a specific form of my invention I wish it understood that the same may be 55 varied, within the scope of the appended claims, without departing from the spirit thereof.

While I have described and illustrated my invention, what I claim and desire to secure 60 by Letters Patent is:

1. In a drier the combination with a revolving drum, of a helix mounted in said drum and adapted to scrape material from the wall thereof and means for adjusting 65 said helix in relation to said wall.

2. In a drier the combination with a revolving drum, of a furnace opening into one end of said drum and a fire-box contained within said furnace, the walls of said fire-box being spaced away from the walls 70 of said furnace and terminating below the top thereof.

3. In a drier the combination with a revolving drum, of a furnace opening into one 75 end of said drum; a fire-box contained within said furnace, the walls of said fire-box being spaced away from the walls of said furnace and terminating below the top thereof and means for admitting air between 80 said spaced walls.

4. In a drier the combination with a revolving drum, of a furnace opening into one end of said drum; a fire-box contained within said furnace, the walls of said fire-box 85 being spaced away from the walls of said furnace and terminating below the top thereof; a closed bottom in said fire-box and means for allowing air to pass under said closed bottom and into the space between 90 said spaced walls.

5. In a drier the combination with a revolving drum, of a furnace opening into one end of said drum and a fire-box contained within said furnace, the walls of said fire-box being spaced away from the walls of 95 said furnace.

In testimony whereof I affix my signature.

ARTHUR C. DAMAN.
